US00D725836S

(12) **United States Design Patent**
Avalos Sartorio et al.

(10) **Patent No.:** **US D725,836 S**
(b4) **Date of Patent:** **** Mar. 31, 2015**

(54) **FOOD PLATE FOR PETS**

(71) Applicants: **Miguel José Avalos Sartorio**, Zapata (MX); **Carlos José Avalos Sartorio**, Zapata (MX)

(72) Inventors: **Miguel José Avalos Sartorio**, Zapata (MX); **Carlos José Avalos Sartorio**, Zapata (MX)

(**) Term: **14 Years**

(21) Appl. No.: **29/499,858**

(22) Filed: **Aug. 19, 2014**

(30) **Foreign Application Priority Data**

Mar. 12, 2014 (MX) MX/f/2014/000832

(51) **LOC (10) Cl.** **30-03**

(52) **U.S. Cl.**

USPC **D30/129**; D30/133; D30/121

(58) **Field of Classification Search**

USPC D30/133, 121, 128, 130, 132, 122, 129; 119/52.1, 55, 61.5–61.56, 51.01, 119/51.03, 59, 62, 63, 51.5, 57.8, 74, 61; D6/480–485; 248/188, 151; 312/204; 108/153.1–157; 220/23.87, 630, 737, 220/743, 9.4, 495.01, 574, 212, 255, 23.83, 220/575; 206/515; D7/586, 543, 550.1, D7/587, 505, 584, 545, 500, 553.1–553.8, D7/546, 555, 556, 504, 565, 562, 602, 507, D7/549, 558, 552.2, 560, 566, 548, 681; D9/429; 43/109; D22/122; 99/430, 99/DIG. 15

See application file for complete search history.

(57) **CLAIM**

The ornamental design for a food plate for pets, as shown and described.

DESCRIPTION

FIG. 1 is a perspective view of the food plate for pets showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

1 Claim, 7 Drawing Sheets
